(57) **CLAIM**

The ornamental design for an ashtray apparatus having a
removable handle, as shown and described.

DESCRIPTION

FIG. 1 is a perspective view of the ashtray apparatus having
a removable handle, showing the handle in an attached
configuration;

FIG. 2 is a side elevational view thereof;

FIG. 3 is a back elevational view thereof;

FIG. 4 is a front elevational view thereof;

FIG. 5 is a top plan view thereof;

FIG. 6 is a bottom plan view thereof;

FIG. 7 is a side elevational view thereof when the handle is
detached therefrom;

FIG. 8 is a back elevational view thereof when the handle is
detached therefrom;

FIG. 9 is a front elevational view thereof when the handle is
detached therefrom;

FIG. 10 is a top plan view thereof when the handle is
detached therefrom; and,

FIG. 11 is a bottom plan view thereof when the handle is
detached therefrom.

It is understood that the opposite side views of FIGS. 2 and
7 are respective mirror images.

For convenience of illustration, the ashtray is disclosed with
the handle removed.
